METHOD OF MAKING TOY FIGURES

Filed Jan. 29, 1930

INVENTOR.
Victor Heney
BY, Julian P. Blackley
ATTORNEY

UNITED STATES PATENT OFFICE

VICTOR KENEY, OF NEW YORK, N. Y.

METHOD OF MAKING TOY FIGURES

Application filed January 29, 1930. Serial No. 424,241.

This invention relates to new and useful improvements in a doll's head and the like, and a process for the manufacture of the same.

5 The invention has for an object the provision of an article of the class mentioned which is of simple durable construction, dependable in use and efficient in action, and which can be manufactured and sold at a reasonable 10 cost.

The invention proposes a doll's head consisting of a form, and a fabric glued on the outside of said form and painted to simulate features. It is proposed to construct the 15 form of paper pulp, paper plaster or composition and the fabric of knitted material so as to closely fit upon the form. It is further proposed that said fabric be of tubular shape having an open bottom and sewed closed at 20 the top upon said form.

The invention has for a further object to make a painted feature upon the fabric movable or changeable upon motion of certain 25 portions of said fabric. The invention also proposes a method for engaging a tubular knitted fabric capable of stretching over a form previously covered with liquid glue, sewing the opened top of the tubular form closed so that it tightly fits the form, and 30 applying coloring upon the form to form features.

It is a further object of this invention to provide a method for the manufacturing of the article mentioned, which includes engaging a dome shape feature colored knitted 35 fabric capable of stretching over a form previously covered with liquid glue so that like features of the fabric and form coincide.

For further comprehension of the invention, and of the objects and advantages thereof, reference will be had to the following description and accompanying drawings, and to the appended claims in which the various 40 novel features of the invention are more particularly set forth.

In the accompanying drawing forming a material part of this disclosure:—

Fig. 1 is a side elevational view of a doll's head constructed according to this invention.

Fig. 2 is a front elevational view of a doll's

head similar to Fig. 1, but illustrating a modification of the invention.

Fig. 3 is a fragmentary horizontal sectional view taken on the line 3—3 of Fig. 1.

Fig. 4 is a fragmentary plan view of Fig. 1. 55

Fig. 5 is a fragmentary horizontal sectional view taken on the line 5—5 of Fig. 2.

Fig. 6 is a fragmentary sectional view taken on the line 6—6 of Fig. 2.

In Figs. 1, 3 and 4 a tubular knitted fabric 60 10 capable of stretching has been shown engaged upon a form 11. The fabric 10 need not be knitted as long as it may stretch to snugly engage the form. The form is shaped to present various features, such as eye brows 65 12, eye balls 13, a nose 14, cheeks 15, etc. The tube before engaged upon the form should be of a sufficiently small diameter so that it must be stretched, and then when engaged snugly fits the form. 70

The fabric 10 is pasted, glued or similarly secured upon the form. The fabric tube 10 is closed at the top by gathering it as indicated by reference numeral 16 and then applying stitches 17 to sew it closed. It should be so sewn that it tightly engages the form and simulates hair. Coloring is applied on the fabric so as to simulate various features, such as eye brows 12', eye balls 13', a nose 14', cheeks 15' and so on. And all of these 75 features upon the fabric should be congruent with the features of the form so that a doll's head or other object is produced. 80

The form 11 as shown is of hollow construction and preferably composed of wood pulp, paper plaster, composition or the like. The lower end of the fabric indicated by reference numeral 18 is shown torn off from the form and turned upwards merely for illustration purposes. 85

The method for manufacturing the doll's head shown in Figs. 1, 3 and 4, consists in engaging a tubular knitted fabric of a length slightly longer than the length of the form and of a diameter smaller than the diameter 90 of the form and capable of being stretched, over the form which has previously been covered with liquid glue, than sewing the top of the tubular fabric together to close the top and cause it to snugly engage against. 100

the form and produce gathering simulating hair. After the glue which secures the fabric upon the form has dried, coloring may be applied to simulate various features.

In Figs. 2 and 5, a modified form of the device has been disclosed which consists in a dome shaped fabric 10^a engaged upon the form 11 in a manner similar to the preferred form just described. The dome shaped fabric is of a size slightly smaller than the form so that when engaged on the form it must be stretched and thereafter snugly engages all portions of the form. Since it is of dome shape, it is closed at the top and may be properly painted to simulate hair. The fabric 10 used in Figs. 1, 3 and 4 has a rear seam indicated by reference numeral 20. This seam is produced when the fabric is knitted upon a full-fashioned knitting machine. The fabric 10^a as shown in Fig. 2 has no seam whatsoever and may be produced upon a circular knitting machine.

The process of manufacturing the device as shown in Figs. 2 and 5 is similar to the one previously described and may be reviewed as consisting in engaging the dome shaped knitted fabric capable of stretching over the form previously covered with liquid glue. Another way of carrying out the method would be to paint the features upon the fabric before applying it upon the form and when applied upon the form so positioning it that like features of the form and fabric coincide.

In Fig. 6, a modified form of the device has been illustrated which consists in a form 11, and a fabric 10^a engaged on the form. The form has various features, such as eye brows 12, eye balls 13, etc. The fabric has similar features coinciding with the features on the form. Reference numeral 12' indicates the eye brow features upon the fabric and 13' the eye ball features upon the fabric. The fabric is only partially glued to the form so as to be held down in portions only, providing loose portions which may be moved. The heavy line 22 between a portion of the fabric and the form indicates glue holding these parts together at those portions only, providing a space 23 between other portions. Amusement may be had by pulling the loose portions of the fabric so as to change the expression of the features. Thus, if the loose portions shown in Fig. 6 would be pulled, the eye brows upon the fabric could be moved. It is to be understood that the top gathering may be replaced by stitches and that the entire doll body may be made by the same process or animal bodies may also be simulated.

It is also to be understood that the covering material may be of any suitable fabric, such as sateen, felt, etc.

While I have shown and described the preferred embodiment of my invention, it is to be understood that I do not limit myself to

the precise construction herein disclosed and the right is reserved to all changes and modifications coming within the scope of the invention as defined in the appended claims.

Having thus described my invention, what I claim as new, and desire to secure by United States Letters Patent is:—

1. A method for manufacturing a doll's head or similar article, consisting in engaging a tubular knitted fabric of smaller diameter than a form and capable of stretching over said form, previously partially covering said form with liquid glue, sewing the opened top of the tubular fabric closed so that it tightly engages the form and applying coloring upon the fabric to form features. 80

2. In a method for manufacturing a doll's head of the class described, the step of engaging a dome shaped knitted fabric capable of stretching over a form previously partially covered with liquid glue, said fabric before engagement upon the form being of a size smaller than the form so that when engaged it snugly engages the form. 85

3. In a method for the manufacture of a doll's head, the steps of forcing a tubular knitted fabric of a smaller diameter than a certain form upon said form so that upon subsequent contraction it assumes the shape of the sides of the form, and sewing the open top of said tubular fabric together so as to hold said portion to the shape of the form. 90

In testimony whereof I have affixed my signature.

VICTOR KENEY.
